FISHING ROD HANDLE

John Sargeant McGuire, Kansas City, Mo.

Application August 28, 1948, Serial No. 148,351

Term of patent 14 years

(Cl. D31—4)

To all whom it may concern:

Be it known that I, John Sargeant McGuire, a citizen of the United States, residing at Kansas City, in the county of Jackson and State of Missouri, have invented a new, original, and ornamental Design for Fishing Rod Handles, of which the following is a specification, reference being had to the accompanying drawing, forming part thereof.

Fig. 1 is a perspective view of a fishing rod handle showing my new design.

Fig. 2 is an end elevation of the fishing rod handle.

Fig. 3 is a plan view of the fishing rod handle.

Fig. 4 is a side elevation of the fishing rod handle.

I claim:

The ornamental design for a fishing rod handle, as shown.

JOHN SARGEANT McGUIRE.
